CIGAR PIERCING APPARATUS

Benjamin J. Niemezynski, Bronx, and Joseph B. Midulla, New York, N. Y., and Joseph D. Midulla, Tampa, Fla.

Application February 20, 1941, Serial No. 379,876

4 Claims. (Cl. 131—254)

This invention relates to an apparatus for piercing or perforating the ends of cigars and the like to provide a small axial bore in one of the ends thereof in order that the cigars may be smoked without the necessity of the smoker biting or cutting off the ends in order to permit the cigar to "draw" properly.

More particularly, the invention relates to motor, or power-driven, cigar piercing apparatus primarily designed to be used by manufacturers or importers for piercing the ends of the cigars before they are packaged for the retail trade.

An object of the invention is the provision of a rotary cigar tip piercing apparatus having a rotary tubular cutter which is cylindrical in cross section, and means for collecting the dust or cuttings from the cigars and subsequently discharging these cuttings from the collecting means into a collection chamber.

Another object is to provide a cigar piercing instrumentality which is mounted in a substantially horizontal plane, and in which provision is made for preventing axial displacement of the cutter during the cigar piercing operation.

A further object is the provision of cigar guide means disposed adjacent the cutter for receiving the end of the cigar to be pierced, and constructed to support one end of the cigar in axial alignment with the cutter during the piercing operation.

A still further object is the provision of a rotary piercing head in which the outer and inner surfaces are circular in cross section and both of said surfaces taper outwardly away from the cutting end, the inner surface constituting an axial bore, and a rotary supporting sleeve member in which the tubular tapered cutter is removably mounted, said sleeve member having an elongated receiving chamber for the cigar dust and cuttings and radial discharge openings formed therein.

A still further object is the provision of a stationary dust-collecting casing surrounding the aforementioned sleeve or receiving chamber for receiving the cuttings discharged from the receiving chamber through said radial discharge openings, and collecting means removably disposed in the casing.

Another object is the provision of means surrounding the sleeve member for slidably and yieldably supporting the cigar guide means in axial alignment with the rotary cutter.

A still further object is the provision of a novel and improved cigar piercing assembly as herein-after more specifically described.

In the drawing:

Figure 1 is a vertical longitudinal sectional view of our improved cigar piercing apparatus, the full lines showing a cigar after it has been pierced, and the dotted lines illustrating the cigar and its guide means in the initial position before engagement of the cigar with the piercing cutter;

Figure 2 is a vertical transverse sectional view taken approximately on the line 2—2 of Figure 1; and

Figure 3 is a vertical sectional view on the line 3—3 of Figure 1.

Like reference characters refer to like parts in the several figures of the drawing in which A indicates a horizontal supporting surface, such as a work-bench or table top, on which our improved cigar tip piercing device is mounted.

As best seen in Figure 1, we preferably mount our cutter on the rotary drive shaft of a motor B, this shaft being indicated at 1, and the rotary cutter and supporting barrel or sleeve member thereof being indicated generally at 2.

This barrel 2 is provided at 3 with an enlarged chamber intermediate its ends and a bore or axial opening 4 for receiving the motor shaft 1. The barrel is held in place on the shaft 1 by set-screw fastening means 5, or in any other suitable manner.

20 The cigar tip piercing cutter is indicated generally at 6, and is securely held in place in the other end of the barrel 2 by the set-screw fastening means 7.

The cutter 6 comprises an elongated tapered tubular portion having a sharp cutting edge 8, and a central bore or passage 9 which tapers from the barrel supporting end to the cutting edge 8. The outer surface 10 of the cutter also tapers from its base or rear end toward the cutting edge 8 as indicated, and is preferably formed with a cylindrical supporting portion 11. The cylindrical portion 11 of the cutter is securely disposed in a bushing 12, by a tight or press-fit between the cylindrical portion 11 and the cutter-receiving bore in the bushing.

The cutter 6 and bushing 12 are removably disposed as a unit in the end of the barrel 2, as seen in Figure 1 of the drawing, and held in place by set-screw fastening means 7, as previously referred to.

The barrel 2 is provided intermediate its ends with radial discharge openings 14, leading from the chamber 3 to the exterior for discharging the tobacco dust and cuttings that pass through the

tapered bore 9 of the cutter 6 and into the chamber 3.

Surrounding the barrel 2 in the plane of the radial discharge openings 14 is a dust collection chamber or casing 15. This casing, as shown in the drawing, rests on the supporting surface A and is held in position thereon by bolts or other suitable fastening means 16. The casing is preferably closed at its top, ends, and sides, the side plates thereof being apertured, if desired, as indicated at 17, for inspecting the interior of the casing 15, to determine the amount of dust which has been discharged from the barrel 2 through the openings 14 into the chamber or casing 15.

Removably disposed in the lower portion of the casing 15 below the rotary barrel 2 is a removable receptacle 18, as best seen in Figure 3, to collect the discharged tobacco dust and cuttings. This receptacle 18 is provided with a handle 19 to facilitate the removal thereof from the casing.

The casing 15 is formed with a cylindrical barrel-receiving opening 20 of slightly larger diameter than the exterior surface of the rotary barrel 2, so that the barrel may freely rotate in this opening 20 entirely out of frictional contact with the casing 15.

Upstanding from the supporting base A between the collection chamber 15 and the cutter receiving end of the barrel 2, as seen in Figure 1 of the drawing and indicated at 21, is a support or bracket member for the cigar supporting and guiding means which receives the tip end of the cigar to be pierced and guides the same into the cutting edge 8 of the cutter 6.

This supporting means 21, as shown, comprises a short length of rectangular tubing, and bolt fastening means 22 pass through the bottom side to secure the same in place on the supporting surface A. A sleeve bearing 23 is secured in place in the openings in the vertical walls 21a of the supporting means, and is positioned in axial alignment with the axis of rotation of the barrel 2.

The sleeve bearing 23 is spaced from the exterior surface of the barrel and slidably receives therein the cigar guide supporting tube 24. This tube 24 slides within the sleeve bearing 23 and is preferably provided with a pin projection 25 operating in a slot 26 formed in the sleeve 23 to limit the extreme sliding movements of the tube 24 within the sleeve bearing. A light coil spring 27 surrounds the outer end of the tube 24 beyond the end of the guide sleeve 23. One end of this spring bears against the end of the sleeve 23, and the other end of the spring is bent at right angles, as indicated at 27a, and projects into and through an aperture 28 in the outer end of the tube 24.

The tube 24 is counter-bored, as indicated at 29, to accommodate a cigar tip receiving thimble 30. The outer surface of this thimble 30 is formed with a recess 30a to receive the bent end portion 27a of the spring 27. When the spring 27 is in place on the tube 24 it will not only exert outward thrust on the tube with respect to its supporting sleeve bearing 23, but the end of the spring projecting through the opening 28 of the tube 24 into the aperture 30a of the thimble 30 forms an interlocking connection between the tube 24 and the thimble 30 and prevents accidental displacement of the thimble from the tube.

The thimble 30 is formed with a cigar tip receiving recess or depression 31 having a central aperture 32 of slightly greater diameter than the exterior tapered surface 10 of the piercing cutter 6.

The guide tube 24 and its cigar-receiving thimble are normally projected forwardly to the dotted

line position as indicated by the arrow X in Figure 1, so that the cutter 6 is disposed within the central aperture 32 and below the bottom of the cigar-receiving depression 31 of the thimble 30 with the pin 25 at the lefthand or outer end of the slot 26 in the guide tube 23.

It should be here observed that the bore through the tube 24 is of greater diameter than the outer surface of the barrel 2, so that the barrel 2 and tube 24 are out of frictional contact with each other. The barrel 2 and its cutter 6 are carried primarily by the shaft 1 of the motor B, and the motor B is secured on the supporting surface A by any suitable fastening means, such as the screws 33.

The vertical side walls 21a of the rectangular tubular supporting means 21 may be provided with openings 34 for inspection purposes and for access to the sleeve 23, and the pin and slot connections 25-26.

In the operation of our device, the motor is started which causes a high speed rotation of the barrel and its cigar piercing cutter 6, the guide tube 24 and its cigar receiving thimble 30 remaining stationary.

The end of a cigar C is inserted into the depression 31 of the thimble 30, centralizing that end of the cigar with respect to the cutter 6. The cigar is held in approximately axial alignment with the axis of the rotating cutter and pressure is applied to the cigar in the direction toward the cutter 6, causing the spring 27 to yield and the thimble 30 supporting the end of the cigar and its supporting tube 24 to move inwardly. The end of the cigar engages the cutting edge 8 of the tapered cutter 6, and the cutter enters the tip end of the cigar, as shown in full lines in Figure 1 of the drawing, the guide tube 24 and thimble 30 moving inwardly to the position shown by the arrow Y.

Dust and cuttings from the cigar pass into the tapered bore 9 of the cutter 6, and are assisted by centrifugal action of the rotating cutter in its movement through the bore and into the chamber 3. These cuttings will be more or less held against the inner surface of the barrel by the centrifugal action, but as the force of centrifugal action is less near the axial center of the barrel 2, the inner portion of the accumulation of tobacco dust and cuttings in the chamber 3 of the barrel 2 will be gradually fed toward the radial openings 14 and discharged therethrough by centrifugal force into the casing 15 and deposited in the receptacle 18, which may be readily emptied when desired.

The thimble 30 securely holds the tip portion of the cigar in proper alignment with the rotary cutter 6 during the cutting operation, the curved walls of the depression 31 in the thimble exerting radially inward pressure on the exterior tip portion of the cigar tending to resist splitting of the cigar wrapper.

The friction of the exterior surface 10 of the rapidly rotating cutter 6 on the cigar as it follows the cutting edge 8 into the cigar creates heat which serves to soften the adhesive usually on the tip of most all cigars, reducing splitting and, in addition, producing a burnishing effect on the walls of the hole being formed in the cigar, and forming a smooth, clean hole, free from loose material which would tend to interfere with the "draw" of the cigar. The edge of the wrapper in the vicinity of the hole is also somewhat rolled into the opening being formed by the rapidly rotating tapered cutter, creating a very

pleasing and smooth appearance of the wrapper around the hole.

In order to withdraw the cutter from the cigar, the holding pressure on the cigar is released. The spring 27 will move the tube 24 and its thimble 30 back to the position shown by the arrow X, and the cigar may be withdrawn from the depression 31 in the thimble 30.

The tapered bore 9 through the cutter 6 will positively prevent the tobacco dust and cuttings from the cigars, which contains a certain amount of gum adhesive, clogging the bore, as would be the case if a straight or cylindrical bore through the cutter 6 were used. Also, any slight lateral movement of the unsupported end of the cigar as it is withdrawn from the cutter will not tend to split the wrapper, since slight withdrawing movement of the tapered outer surface 10 of the cutter 6 moves the cutter out of contact with the tapered bore which has been formed in the cigar.

While the specific details of construction have been herein shown and described, the invention is not confined thereto as alterations may be made without departing from the spirit thereof as defined by the appended claims.

Having thus described our invention, what we claim as new and desire to secure by Letters Patent is:

1. In a piercing cutter of the class described, a rotary support, a tubular member carried at one end by said support for rotation therewith and formed with an elongated central passage having radial discharge openings through the wall thereof intermediate the ends of the passage, a tubular piercing cutter removably fixed in the opposite end of the central passage in said tubular member with its longitudinal axis in alignment with the axis of rotation of the rotary support and having a cutting edge at one end and an axial passage leading from the cutting edge into the elongated central passage of said tubular member, a casing surrounding said tubular member intermediate its ends and having spaced side walls located adjacent the opposite sides of the radial discharge openings, and a collection receptacle removably disposed in said casing below said tubular member intermediate said side walls.

2. In a cigar piercing apparatus of the class described, a rotary cylindrical barrel having a tapered tubular cutter at one end thereof formed with a circular cutting edge at its free end, and having a tapered bore extending therethrough from the cutting edge into said barrel, discharge openings extending through the wall of the barrel from the interior thereof to its exterior, cigar guide means movable axially with respect to said barrel and cutter, comprising a sleeve member receiving one end of said barrel and a thimble disposed in one end of said sleeve member having a cigar tip-receiving depression therein and an axial opening therethrough to receive the tapered tubular cutter, a fixed tubular support for said sleeve, coil spring means surrounding said sleeve having one end thereof engaging one end of said tubular support and the other end extending through said sleeve and into said thim-

ble to interlock said sleeve and thimble together and to exert yieldable axial pressure on the said guide means, a casing surrounding said barrel having substantially parallel side walls disposed transversely of the axis of rotation of the barrel and cutter, and disposed at each side of the openings through the wall of said barrel and formed with a circular opening therethrough to receive the said barrel, and means for rotating said barrel and cutter.

3. In a cigar apparatus of the class described, a rotary cylindrical barrel having an unobstructed axial bore extending therethrough with an enlarged intermediate portion, a tubular cutter in one end of said barrel having a circular cutting edge and an axial bore extending into said unobstructed axial bore of the barrel, said barrel having radial openings through the wall thereof in communication with the elongated intermediate portion of said bore, axially movable cigar guide means surrounding said cutter and one end of said barrel and having an opening therethrough to receive said tubular cutter and formed with a cigar tip-receiving depression surrounding said cutter receiving opening, a stationary tubular support slidably receiving said guide means therein, means for preventing rotation of said guide means and limiting the axial movement of said guide means with respect to said tubular support, a collection casing surrounding said barrel having side walls disposed at opposite sides of the openings in the wall of the barrel, and formed with barrel receiving openings through said side walls, and a support for said stationary tubular support having parallel side walls formed with openings therein to receive the opposite ends of said stationary tubular support.

4. In a cigar piercing apparatus of the class described, an elongated rotary tubular member, a tubular cigar piercing cutter at one end thereof, cigar guide means therefor comprising spaced supporting plates surrounding said tubular member intermediate the ends thereof, and formed with enlarged guide bushing receiving openings therein, a guide bushing fixed in said openings adapted to receive said tubular member intermediate the ends thereof and in spaced relation thereto, a cigar guide sleeve telescopically mounted within said guide bushing having one end thereof adapted to project beyond the said tubular cutter, and being adapted to slide over said tubular member to expose said cutter, stop means for limiting the said sliding movement between said sleeve and bushing, and spring means between said sleeve and bushing for moving said sleeve outwardly over the tubular member and cutter, said sleeve member having formed in the outer end thereof a cigar tip-receiving depression having an opening therethrough to receive said cutter and adapted to guide the tip end of a cigar disposed in said depression into said piercing cutter.
